UNITED STATES PATENT OFFICE.

GEORGE CLARY, OF ZACATECAS, MEXICO, AND GEORGE W. GARRISON, OF GOLDFIELD, COLORADO.

HEARTH FOR ROASTING ORES.

SPECIFICATION forming part of Letters Patent No. 660,982, dated October 30, 1900.

Application filed February 6, 1900. Serial No. 4,109. (No model.)

To all whom it may concern:

Be it known that we, GEORGE CLARY, of the city of Zacatecas, Republic of Mexico, and GEORGE W. GARRISON, of the city of Goldfield, Teller county, State of Colorado, have invented certain new and useful Improvements in Hearths for Roasting Ores, of which the following is a full, clear, and exact description, reference being had to the accompanying drawings, forming a part hereof.

This invention relates to hearths for roasting ore; and it consists of the novel construction, combination, and arrangement of parts hereinafter shown, described, and claimed.

The object of this invention is to construct a device for roasting ore and provide a means for reciprocating the same, whereby the ore is caused to roll over a certain space during the process of roasting.

Figure 1 is a side elevation of our improved hearth for roasting ore. Fig. 2 is a top plan view. Fig. 3 is a detail sectional view. Fig. 4 is a view showing the means by which the device is reciprocated. Fig. 5 shows one of the cams which we make use of in carrying out our invention. Fig. 6 shows the chain connecting the elevating-screws. Fig. 7 is a side elevation of a furnace in which our improved ore-roasting hearth may be used. Fig. 8 is a front end elevation of the same. Fig. 9 is a longitudinal vertical sectional view showing the position of the ore-roaster in the furnace. Fig. 10 is a cross-sectional view taken approximately on the line *a a* of Fig. 9.

Referring by numerals to the accompanying drawings, 1 indicates a bed-plate rigidly held in position by means of bolts 2. Carried at suitable intervals upon each side of the plate 1 are a plurality of bearings 3, rotatably journaled in which are rollers 4. Journaled in bearings 5 on the rear end of the frame 1 is an operating-shaft 6, provided on one end with a belt-pulley 7. Rigidly carried upon the said shaft between the bearings 5 are a plurality of levers or cams 8, there being a depression in the plate 1, allowing the said cams to turn with the shaft 6.

Carried upon the rollers 4 is a frame 9, which is of such length that it projects at each end a suitable distance beyond the end rollers and is provided at its rear end with the integral trans-

verse member 10, against which the cams 8 operate. Journaled in bearings 11 on each side of the frame 9 is a shaft 12, each of which is provided with worm-screws 13. The said screws 13 operate upon worm-wheels 14, through each of which is threaded a screw 15, flattened at their upper ends 16. The said flattened portion of the screws projects into squared apertures 17 in the bottom 18 of the table. This is for the purpose of preventing the said screws from turning when the shafts 12 are turned, but allowing them to be raised by the worm-wheels 14, thereby elevating the table. The rear end of each of the shafts 12 carries a sprocket-wheel 19, around which passes the chain 20. One of the said shafts carries a hand-wheel 21 on its forward end for the purpose of rotating the said shaft when it is desired to raise or lower the table. The screws 15 being at different distances from the pivot-point of the table necessitate that the screws at the rear of the table have threads of greater pitch than those nearer the pivot in order that they may be raised more rapidly and about against the bottom of the table at all times. In other respects the arrangement of the screws is the same.

Supported on the rear end of the plate 1 is a bracket 22, carried by which and by the member 10 are a plurality of bolts 23, around which are carried expansive coil-springs 23, their ends resting against the bracket 22 and the member 10. The said bolts are provided with integral heads 24, which when the device is not in use rest against the bracket 22.

The table which we employ comprises the bottom 18 and the sloping top 25, the rear end of which is higher than the front, the front end being pivotally secured to the upwardly-projecting arms 26 integral with the frame 9. Carried upon the top 25 is a box or receptacle 27, within which is carried a suitable bottom or base 28. Upon the base 28, within the receptacle 27, are placed a plurality of sections 29 of corrugated fire-clay. The arrangement of the parts just described and the corrugations of the fire-clay are best shown in Fig. 3.

The improved ore-roasting hearth may be used in furnaces of any desired construction, but is especially adapted for use in a furnace constructed as shown in Figs. 7 to 10, in-

clusive. In a furnace of this construction the ore-roaster is secured rigidly upon a suitable foundation 30, the shaft 6 projecting through, and the pulley 7 being located exteriorly of, the furnace-walls, as shown in Fig. 8. The fire-box 31 is located a suitable distance in front of the ore-roaster and its foundation and is separated therefrom by a discharge-pit 32, into which the ore falls after it has been sufficiently roasted. The heat and products of combustion from the fire-box are drawn rearwardly over the furnace and pass out through the smoke-stack 33. The ore is placed upon the ore-roaster through hoppers 34, located on the top of the furnace, and after being roasted is removed from the discharge-pit through a suitable door 35 provided for that purpose. 36 denotes an arch or covering extending over the springs 23, the function thereof being to shield the said springs from the heat, thereby preserving their full power. Doors 37 are provided at suitable intervals and afford a ready means for inspecting springs and the other mechanism at any time. To the rear of the ore-roaster are dust-chambers 38, access to which is had through doors 39.

When it is desired to use the ore-roaster, a driving-belt is then applied to the belt-pulley 7, rotating the same, together with the shaft 6 and the cams or levers 8 carried thereby. This operation throws the ends of the levers or cams against the member 10 twice during each revolution. This pushes the frame 9 and all the parts carried thereby rearwardly until the cams have passed out of contact with the member 10. When the cams have passed beyond contact with the said member 10, the springs 23, having been compressed, expand to their normal position and throw the frame 9 forwardly, together with all the parts carried thereby, and the said forward movement is suddenly stopped with a jerk by the bolt-heads 24 coming against the bracket 45 22. This operation is continued twice during each revolution of the cams and, as may be readily understood, the ore upon the corrugated fire-clay would be rolled over and over by the continued reciprocating and jerking movement.

An ore-roasting hearth of our improved construction presents many advantages over all others, is simple, and easily operated.

It may readily be seen that the cost involved in the construction of a device as herein described would not necessarily be greater than for those of ordinary construction. 55

We claim—

1. In an ore-roasting hearth, a plate, rollers carried by said plate, a frame mounted on said rollers, a table having an inclined top pivoted to said frame, a shaft supported by the said plate, means carried by said shaft for moving the said frame and table rearwardly when the said shaft is operated, and a separate means for throwing the said frame and table forwardly, substantially as specified. 60

2. In an ore-roasting hearth, a frame supported on rollers, an inclined table having its forward end pivoted to said frame, the rear end of said table being free, means for raising and lowering the free end of said table, and means for reciprocating said frame and table endwise, substantially as specified. 70

3. In an ore-roaster, a plate, a plurality of rollers carried by said plate, a frame mounted upon said rollers, a table carried by said frame and being pivoted at one end thereto, means carried by said plate for moving said frame rearwardly, a separate means for moving the table forwardly, and means for raising and lowering the free end of said table, substantially as specified. 75

4. In an ore-roasting hearth, a frame, a table carried by said frame, means for raising and lowering the rear end of said table, a receptacle upon said table, and sections of corrugated fire-clay removably carried within said receptacle, substantially as specified. 80

In testimony whereof we affix our signatures in the presence of witnesses.
